UNITED STATES PATENT OFFICE.

THOMAS C. CANDLISH, OF NEW YORK, N. Y., ASSIGNOR TO A. KIMBALL COMPANY, OF NEW YORK, N. Y., A CORPORATION OF NEW YORK.

FIN-TICKET.

1,116,796.

Specification of Letters Patent.

Patented Nov. 10, 1914.

Application filed October 16, 1913. Serial No. 795,592.

To all whom it may concern:

Be it known that I, THOMAS C. CANDLISH, a citizen of the United States, residing at New York, county of New York, and State 5 of New York, have invented an Improvement in Pin-Tickets, of which the following description, in connection with the accompanying drawing, is a specification, like characters on the drawing representing like parts.

10 This invention has for its object the production of a convenient and useful pin ticket for marking fabrics, garments and the like with the price, lot numbers, size or such other information as may be desired, which 15 can be easily applied and removed, the ticket being so constructed that when applied there will be no projecting points to prick the fingers or snag other merchandise.

My improved ticket consists of a blank 20 which may be made from metal or paper of sufficient stiffness and resiliency and a pin secured to one end thereof and extending longitudinally of the ticket. The opposite end of the blank is bent to form a protecting 25 flap, a hole being provided therein through which the point of the pin may extend when the ticket is applied. This flap is so constructed that when the ticket is applied the pin will extend through and beyond the 30 hole and be concealed and protected between the flap and the body of the ticket and the end of the flap with the goods will be positioned between the pin and the body of the blank to be frictionally retained in this position.

For general use in marking merchandise I prefer to make this ticket of stiff paper or 40 card board. When made of flexible metal my improved ticket is adapted to be used for marking goods for laundrying, dyeing and similar operations.

The novel features of my invention will be fully disclosed in the following specification and accompanying drawing, and will 45 be particularly pointed out in the claims.

Referring to the drawing in which I have illustrated my invention:

Figure 1 is a perspective view of a preferred form of my improved pin ticket; 50 Fig. 2 is a similar view of another form of my invention; Fig. 3 is a central longitudinal section showing my improved ticket as applied to the fabric, and Figs. 4 and 5 are longitudinal sections illustrating method of 55 applying my improved ticket to the fabric.

Referring to the drawing in detail, 1 indicates a card made from resilient material a pin 2 being secured to one end thereof and extending parallel to the card. The opposite end of the card is transversely scored, as indicated at 3 to provide a folding flap 4. This flap is provided with a hole 5 and is transversely scored as indicated at 6 and 7, near the inner and outer edges respectively of the hole to provide longitudinal flexibility of the flap. The pin is shown as rigidly secured by passing it twice through the card and pressing one end firmly against the card on the side which will lie against the fabric when the ticket is applied. The free end is extended parallel to and longitudinally of the card. The pin is of a length to pass through the hole 5 and engage the under side of the flap beyond the hole so as to be concealed and protected between the flap and the body of the card. It is essential that the flap should be longitudinally flexible so that the end of the flap may be bent inwardly toward the body of the ticket and passed forwardly between the pin and the body as the flap is folded over to protect the point of the pin. To produce this flexibility I prefer to score the flap as indicated at 6 and 7 in Fig. 1. The score indicated at 6 is essential and is preferably positioned near the inner edge of the hole. The score indicated at 7 may be omitted, and in Fig. 2 I have illustrated a card in which this score is omitted. The hole is shown as long and narrow. I prefer this shape because the fabric lying between the pin and card at this point will assist in holding the flap in position. This hole may, however, be made of any desired shape so long as the pin passes through the hole in such a manner that the end of the flap lies between the pin and the body of the card.

To apply my ticket to a fabric the pin is passed through the fabric and out again so that a loop of fabric is retained between the 100 pin and body of the card. The flap is then bent and the end passed between the card and the pin, as illustrated in Fig. 4.

The bending of the flap at the score 3 is continued, thereby moving the end of the flap forwardly between the pin and the body of the card, as indicated in Fig. 5, until the flap is substantially parallel to the body of the card. The loop of fabric may then be drawn toward the point of the pin so that 105 110

the goods and the end of the flap will be clamped between the pin and the body of the card, and the end of the pin will bear against the under side of and be retained in position by the flap, all as indicated in Fig. 3. As will be seen, the ticket becomes a protection for the pin and acts as an efficient means to conceal and protect the point. There are thus no projecting points to prick the fingers or snag other merchandise, while at the same time the tag is so constructed that it may be readily applied to fabrics or similar goods and is readily removed when desired.

15 Having fully described my invention, what I claim as new and desire to secure by Letters Patent is:

1. A pin ticket comprising a blank and a pin secured to one end thereof and extending longitudinally of the blank, the opposite end of the blank being folded to form a protecting flap, said flap being longitudinally flexible and provided with a hole to receive the point of said pin, the pin being of a length to extend through said hole and arranged to extend toward the folded ends of the blank and engage the underside of said flap beyond the hole, whereby a portion of the flap may be positioned together with the goods between the pin and the body of the blank and frictionally retained in this position, and the point of the pin may be positioned beyond the hole and between the flap and the body of the blank.

35 2. A pin ticket comprising a blank and a pin secured to one end thereof, the opposite end being bent to form a protecting flap, said flap being flexible and provided with a hole to receive the point of said pin and so arranged that when the ticket is applied to merchandise one end of the flap will lie between the body of the blank and the goods and the pin will extend over the edge of the flap and through the hole and engage the underside of said flap beyond the hole.

40 3. A pin ticket comprising a blank and a pin secured to one end thereof and extending parallel to the body of the blank, the opposite end of the blank being transversely scored to provide a longitudinally flexible flap, said flap having a hole therethrough to receive the point of the pin, the parts being so constructed and arranged that by bending the flap the end of the flap may be passed

between the pin and the body of the blank and the point of the pin inserted through the hole and between the flap and the body of the blank.

4. A pin ticket comprising a blank and a pin secured to one end thereof and extending parallel to the body of the blank, the opposite end of the blank being folded to form a protecting flap, said flap having a hole therethrough and being transversely scored near the inner edge of said hole to provide longitudinal flexibility whereby the flap may be bent and the end passed between the pin and the body of the blank, and the end of the pin passed through the hole and between the flap and body of the blank, the pin being of a length to engage the under side of said flap beyond the hole.

5. A pin ticket comprising a card having a protecting flap extending parallel thereto and a pin secured to the card and extending parallel to the card and toward said protecting flap, said flap being transversely scored to provide longitudinal flexibility and being provided with a hole to receive the point of said pin, whereby the end of the flap may be passed between the pin and body of the flap and the pin passed through said hole and between the flap and body of the blank, said pin being of a length to engage the under side of said flap beyond the hole.

6. A pin ticket comprising a card and a pin secured to one end thereof and extending parallel to the body of the card, the opposite end of the card being folded to form a protecting flap, said flap having a hole therethrough and being transversely scored near the inner and outer edges of said hole to provide longitudinal flexibility, whereby the flap may be bent and the end passed between the pin and the body of the card and the end of the pin may be passed through the hole and between the flap and body of the card, the pin being of a length to engage the under side of said flap beyond the hole.

In testimony whereof, I have signed my name to this specification, in the presence of two subscribing witnesses.

THOS. C. CANDLISH.
